Primary Examiner — Mitchell I. Siegel(74) *Attorney, Agent, or Firm* — Wolf, Greenfield & Sacks, P.C.(57) **CLAIM**

The ornamental design for a lacrosse head, as shown and described.

DESCRIPTION

FIG. 1 is a top, front, right side perspective view of a lacrosse head showing a first embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged perspective view of the encircled portion identified as 8 in FIG. 1.

The dash-dot broken lines represent portions of the lacrosse head that form no part of the claimed design. The dot-dash broken lines represent boundaries of the claimed design and form no part of the claimed design.
